SPINNING-IN DEVICE

Ernest J. Griset, Jr., Asheville, N. C., assignor to
 American Enka Corporation, Enka, N. C., a
 corporation of Delaware

Application November 16, 1951, Serial No. 256,631

2 Claims. (Cl. 68—181)

1

The present invention relates to the liquid treatment of threads running in a system of tubes and more particularly to the introduction of the yarn or thread to be treated into the first tube of the system.

In tube spinning the liquid in each tube acts not only as the treating agent but also as the propelling agent for the thread. The tubes are small and the liquid flows in them at high velocity with the result that the matter of getting the thread to intersect the fluid for entrainment thereby presents considerable difficulty. The magnitude of this difficulty can be appreciated when it is borne in mind that the tube is usually threaded with an end running at a speed of from sixty to one-hundred and fifty meters per minute while the fluid is moving in the tube at an even higher rate.

When the problem described above was finally solved, it was by guiding the running thread to a temporary storage device through a path having a point lying adjacent the ingress end of the first tube of the system, cutting the thread near said point and washing the running end into the tube. Further experimentation has confirmed the soundness of this principle of operation but difficulties have been encountered in attempts to simplify the structure of the equipment for providing the thread path and the liquid which washes the thread into the ingress end of the first tube. Various devices to this end are described in application Serial No. 244,115, filed August 29, 1951, and it is an object of this invention to solve the same problem by means which are more rugged, more simple to construct, and easier to operate than were heretofore known.

This invention, therefore, relates to introducing a running thread into a high-velocity liquid stream and has for its objects improved reliability, very low initial and maintenance cost and a high degree of operator convenience.

Other objects and advantages of this invention will be apparent upon consideration of the following detailed description thereof in conjunction with the annexed drawings, wherein:

Figure 1 is a view partially in section and partially in elevation showing a combined thread guide and water supply apparatus according to the present invention in association with the ingress end of one tube of a tube-spinning system; and

Figure 2 is a view in elevation of the combined thread guide and water supply apparatus of the present invention taken from a position 90° to

the right of the position of the same apparatus in Figure 1.

Before describing in detail the thread-introducing device constituting the subject matter of this invention, it is necessary briefly to describe the tube-spinning system, a part of which is shown in Figure 1. The system involves a housing 10 containing an interrupted tube having a feeding-in portion 11 terminating in a nozzle and a treatment portion 12 having a funnel mouth spaced from the nozzle end of the portion 11 to define a venturi at 13. Above the venturi at 13 there is shown a movable trough 14 (although it may be fixed) in a position to discharge into a fixed trough 15, the latter being positioned to discharge into the venturi at 13. The movable trough 14 is in the full-line position of Figure 1 during spinning-in and may be thereafter moved to the broken-line position of that figure in the event it is difficult to shut off the water supply immediately.

When spinning-in is to be initiated, the tube 11 and the other tubes of the system which are not shown are supplied with water or treating liquid. The thread is introduced into the funnel mouth 13 of the tube 12 and is treated and propelled by the liquid entering the tube 12 from the tube 11. The entire system, except for the new thread introducing device is fully shown in copending application Serial No. 122,560, filed October 20, 1949, the disclosure of which is incorporated by reference herein.

The combined spigot and thread guide of the present invention is comprised entirely of a single tube 16. This tube is connected to a water-feed line 17 at its upper end and is supported above the housing 10 by a bracket 18. From the point of connection to the water supply line 17 the tube 16 is continuous until a point is reached where the tube extends in a generally vertical plane above the movable trough 14. At that point the tube 16 is cut away as is clearly shown in Figure 2 to provide an elongate trough terminating at the lower end of the tube 16. At said lower end the tube 16 is provided with a notch 19 between the sides of the channel. Through this notch thread may be withdrawn to a temporary collecting device diagrammatically indicated at 20.

When spinning-in is to be initiated and the liquids are running in the tubes of the system, thread 21 from a suitable source not shown, is led vertically downwardly through the trough provided by the cutting or milling out of the tube 16 to the notch at 19 at which point its

direction is sharply changed and it is led somewhat upwardly to a waste collection device 20. A flow of water is started in the conduit 17 with a resulting cascade over the thread in the channel portion of the tube 16, the cascade discharging into the movable trough 14, the stationary trough 15 and intersecting the path of liquid from the tube 11 to the tube 12. When this condition prevails, the operator cuts the thread 21 at the point X, see Figure 1, whereby the 10 running end is washed through the movable trough 14 and the fixed trough 15 into intersecting relation with the stream flowing from the tube 11 to the tube 12. The running end is entrained by that stream and carried into the tube 12 and so on throughout the system in accordance with the disclosure of application Serial No. 122,560, filed October 20, 1949. The end to the left of the point X of Figure 1 is, of course, reeled up on the temporary collecting device.

It is found that the device of the present invention, because of the length of the channel produced by milling away of one side of the tube 16, reliably guides the thread into the path of the liquid so that it is accurately and surely guided by the liquid to the desired point of intersection with the main stream. It is apparent that the device of the present invention is rugged, durable and about as simple as anything can be comprising as it does but a single part. In use, once the thread has been introduced to the tube 12, water in the conduit 17 is cut off and the thread runs directly in the chain-line path of Figure 1 around a guiding roller 22 to the funnel 13 and it is unnecessary to move trough 14 to the dotted line position.

While the tube 16 is described as being milled

or cut to produce the generally vertical channel, it is, of course, apparent that the same structure can be produced by casting. The tube may be made of any material that is sufficiently resistant to corrosion, lead being particularly suitable.

What is claimed is:

1. Spinning-in device for introducing a thread into a low-pressure zone of a high-velocity stream of liquid that comprises thread delivery means disposed above the zone, a waste thread collecting device disposed above the zone, a generally vertically extending channel terminating in a notch at its lower end disposed between the sides of the channel, said channel having its upper end below the thread delivery means and its notch above said zone but below the waste collecting device and a tubular conduit constituting an integral part of said channel for delivering liquid to the upper end thereof.
2. Spinning-in apparatus for introducing a thread into a low-pressure zone of a high-velocity stream of liquid that comprises, jet means to direct a high velocity stream of water to said zone, a channel generally vertically disposed above said jet means and a tubular conduit constituting an integral part of said channel to deliver liquid thereto, and means to deliver thread to said channel near the upper end thereof.
